UNITED STATES PATENT OFFICE.

HERBERT W. TINKER, OF MILWAUKEE, WISCONSIN, ASSIGNOR TO FEDERAL PRESSED STEEL COMPANY, OF MILWAUKEE, WISCONSIN, A CORPORATION OF WISCONSIN.

DESIGN FOR A BUMPER FOR VEHICLES.

Application filed February 15, 1924. Serial No. 8,640. Term of patent 14 years.

To all whom it may concern:

Be it known that I, HERBERT W. TINKER, a citizen of the United States, residing at Milwaukee, in the county of Milwaukee and State of Wisconsin, have invented a new, original, and ornamental Design for Bumpers for Vehicles, of which the following is a specification, reference being had to the accompanying drawing, forming part hereof.

The figure is a perspective view of a bumper for vehicles, showing my new design.

I claim:

The ornamental design for a bumper for vehicles, as shown.

HERBERT W. TINKER,
